ELECTRON OPTICAL DEVICE

Helmut Johannson, Berlin-Charlottenburg, Germany, assignor to General Electric Company, a corporation of New York

Application July 3, 1935, Serial No. 29,755
In Germany July 4, 1934

2 Claims. (Cl. 250—27.5)

The present invention relates to improvements in electron-optical devices and is directed more particularly to the elimination of distortion and aberration effects obtaining in the use of such 5 devices.

It has been found that when an electron beam discharge generated directly from a cathode member, or indirectly from a target member, is drawn through an apertured diaphragm held at 10 a potential sufficient to develop a definite electrostatic field, a diffusion or refraction of the beam takes place. If the electrostatic field employed is properly placed and suitably adjusted with relation to the velocity of the discharge, this diffusion or refraction of the electron beam may be 15 employed to obtain effects comparable to those achieved by passing light rays through lenticular systems. Thus, if the refracted rays be projected on a screen member located adjacent a 20 highly positive electrode member, a magnified image of the cathode surface, or the target surface, as the case may be, will be produced thereon. By this means it is theoretically possible to obtain magnifications as high as 1 to 10,000.

In the absence of special precautionary measures there is nothing to insure that the distorting effect of the electrostatic diaphragm employed will be such as to produce a perfectly magnified image. Indeed, it has been found that in the 30 conventional system employing as electrodes a cathode and two additional electrodes formed as diaphragms the images reproduced show considerable distortion. This is partly manifested in an unnatural picture curvature and partly in a blurring of the outer edge of the image. In a 35 sense, this latter aspect may be compared with the well-known phenomenon of spherical aberration of optical lenses, wherein the difference in relative curvatures between the center and the edge 40 of the lens results in a plurality of displaced focusing points and a vague and distorted image.

In accordance with my present invention one or more additional grid diaphragms are provided intermediate the focusing aperture and the screen 45 to enhance the quality of the image formed. I have found that by regulating the electrostatic potential of the auxiliary diaphragm both the magnification and the range of sharp definition of the image may be greatly increased.

The novel features which I consider characteristic of my invention are set forth with particularity in the appended claims. The invention itself, however, will best be understood by reference to the following specification taken in connection with the drawing, the single figure of

which represents diagrammatically a four-electrode microscope which may suitably be employed in the practice of my invention.

Referring to the structure illustrated, I provide a surface 1 which may act as an electron beam source. This may alternatively comprise a cathode or other inherently electron-emissive element or a target adapted to give off electrons when bombarded from an electron source. Spaced from the cathode 1 at a distance c 5 variable within limits of from about .5 to 1.5 millimeters is a focusing electrode or diaphragm 2 provided with a central aperture 3. An appropriate size for the aperture I have found to be in the neighborhood of one millimeter. 10

About one-half millimeter from the main focusing grid 2 I provide a second electrode which is also illustrated as an apertured diaphragm or grid 4. This diaphragm, which constitutes means for modifying the electrostatic field adjacent the electrode 2, may suitably be of dimensions comparable with those of that electrode. Approximately one millimeter or less from the second electrode is mounted a third apertured electrode or anode 5 which is capable of being 15 brought to a relatively high positive potential with respect to the emitting source 1. Behind the anode 5 and spaced at a considerable distance therefrom I have shown a projecting screen 6 of fluorescent material suitable for receiving 20 and reproducing the magnified image of the source 1. With other dimensions corresponding to those given above I have found it convenient to use a spacing between the screen and the object being observed which is in the neighborhood 25 of 240 millimeters. It should be understood, however, that this dimension as well as those previously stated are merely exemplary of a particular arrangement which I have found practical in actual tests. Any of the values given may be varied 30 within wide limits provided a reasonable proportionality is maintained which will result in 35 proper focusing of the corpuscular rays.

In the operation of an electron microscope constructed in accordance with my invention the 45 anode 5 is made highly positive with respect to the object source 1. In this way the electrons generated are accelerated to pass at high velocity through the aperture 3 of the diaphragm 2. If the potential of this diaphragm is then lowered, 50 that is, made less positive than the anode or made negative with reference to that of the source electrode 1, a focusing effect will take place quite like that occurring when light rays are passed through a lens system. Finally, by varying the 55

potential of the auxiliary electrode 4 and bringing it to an optimum value the electrostatic field adjacent the focusing electrode may be so modified that a maximum of amplification is obtained 5 coupled with the highest possible picture quality. This optimum value will generally lie between the potential of the electrode 1 and that of the anode being in most instances of the order of magnitude of the latter and accordingly positive with respect to the focusing electrode 2.

Actual experiments have shown that a four-electrode microscope embodying my invention may be made to yield magnification 25 per cent higher than has been found possible with three-electrode assemblies. Furthermore, the introduction of a second grid permits an increase in the diameter of the sharply defined picture surface of about 100 per cent. Changes in these factors, formerly obtainable only by varying the 10 relative spacing of the various electrodes, can now be obtained simply by regulating the potential impressed upon the auxiliary electrode. Additional improvements in reproduction can be accomplished by special formations of the focusing electrodes, such as surrounding the apertures by funnel-like projections.

It is also possible and my invention contemplates that the corrective deformation of the potential field can be brought about by the superposition of a magnetic field on the electrostatic field created by the grid electrodes.

While I have shown a particular embodiment of my invention, it will of course be understood that I do not wish to be limited thereto since many 35 modifications in the structure may be made, and I contemplate by the appended claims to cover all such modifications as fall within the true spirit and scope of my invention.

What I claim as new and desire to secure by 40 Letters Patent of the United States, is:—

1. An electronic magnification device comprising an electron beam source, means for reproducing an enlarged image of the source, and a series of relatively thin closely spaced electrodes interposed between the said source and image-reproducing means and each having a substantially circular opening therein arranged to be traversed by the electron beam, said electrodes including an anode for accelerating the beam toward such means, a focusing electrode between the anode and the source, said focusing electrode being effective when negatively charged with respect to the anode to produce substantial magnification of the beam image on the image-reproducing means, and an intermediate electrode between the focusing electrode and the anode, said intermediate electrode being effective when positively charged with respect to the focusing electrode to increase the region of undistorted magnification of the beam image. 20

2. An electronic magnification device comprising an electron beam source, a fluorescent screen or the like adapted to reproduce an enlarged image of the source and a series of closely spaced apertured diaphragms positioned between the source and the screen, said diaphragms comprising an anode adapted to be maintained at a high positive potential with respect to the beam source, a focusing electrode between the anode and the source, said focusing electrode being effective when negatively charged with respect to the anode to produce substantial magnification of the beam image on the screen, and an intermediate electrode between the focusing electrode and the anode, said intermediate electrode being effective when positively charged with respect to the focusing electrode to increase the region of undistorted magnification of the beam image. 30 35
